UNITED STATES PATENT OFFICE.

JOHANN STUMPF, OF BERLIN, GERMANY, ASSIGNEE TO GENERAL ELECTRIC COMPANY, A CORPORATION OF NEW YORK.

STEAM OR GAS TURBINE.

No. 811,752.

Specification of Letters Patent.

Patented Feb. 6, 1906.

Application filed October 8, 1904. Serial No. 227,353.

To all whom it may concern:

Be it known that I, JOHANN STUMPF, a subject of the King of Prussia, German Emperor, residing at Berlin, Germany, have invented 5 certain new and useful Improvements in Steam or Gas Turbines, of which the following is a specification.

It is well known in connection with elastic-fluid turbines as ordinarily constructed having oppositely-rotating wheels which are so arranged that the motive fluid passes directly from one to the other without the intervention of intermediate or fluid reversing-vanes that the wheel first to receive the motive fluid 15 develops more power than the second wheel. In other words, the primary wheel has a greater capacity for performing useful work than the secondary wheel. This arrangement is useful in connection with certain 20 kinds of work, but is undesirable with others.

It has been proposed to equalize the partial outputs by providing an additional stage for the secondary wheel, comprising a special wheel connected thereto. This obviously involves a complicated construction which takes away the principal advantage afforded by the simple oppositely-running turbine—i. e., that no fluid-conducting means of any kind is necessary between the wheel-buckets.

30 The object of the present invention is to improve the construction of elastic-fluid turbines having oppositely-rotating bucket-wheels, whereby the effective action of the secondary wheel may be improved without 35 the mechanical complications heretofore considered necessary.

In carrying out my invention in its simplest form two wheels are provided and so arranged that the motive fluid passes from one 40 to the other. The buckets on the primary wheel and the nozzles or devices for discharging fluid thereto are designed to give a definite speed under normal load conditions. The buckets on the secondary wheel are so 45 proportioned or formed that the speed of said wheel is greater than that of the primary wheel. In other words, by causing the buckets of the primary and secondary wheels to revolve at different speeds the wheels can be 50 made to perform equal amounts of work, and this without an additional stage.

It is self-evident that my invention is applicable not only to turbines having only two oppositely-rotating wheels, but to multistage

turbines, wherein the several wheels are so arranged that a portion rotates in one direction and the remainder in the opposite.

The invention is particularly useful in connection with marine service wherein oppositely-revolving propeller-shafts are employed. The advantage will be found to be marked aside from the more satisfactory performance of the turbine as a whole.

One wheel is connected to a hollow shaft, while the other is connected to a shaft, usually solid, located within the former. To the end of the shaft carrying the primary wheel is connected a propeller or screw of relatively large diameter, while to the shaft carrying the secondary wheel is connected a propeller or screw of smaller diameter. The smaller screw preferably works in the body of water discharged by the forward or larger screw, and consequently in a stream or current which is moving at a certain velocity. By 75 suitable selection of the shape of the buckets, &c., the secondary wheel may be made to revolve at such a speed that the peripheral speed of the smaller screw is the same or substantially the same as that of the larger screw, 80 and the work performed by the screws will be substantially equal. It is preferable to modify the shape of the buckets of the secondary wheel to obtain the desired results; but under certain conditions it is possible by suitably 85 forming or mounting the blades of the screw or propeller to increase the velocity of the secondary wheel until the work of the two wheels is equal.

When screws are rotated at high speeds, 90 they have a tendency to create a vacuum in the body of fluid adjacent thereto; but this tendency is with my improved construction reduced to a minimum, owing to the fact that the smaller screw, while it makes a greater 95 number of revolutions than the primary propeller, revolves in the current of water set into motion by the forward and larger screw.

By increasing the speed of rotation of the smaller screw the velocity of the larger screw 100 can be relatively reduced. Since the large screw works in relatively quiet water, it is desirable to reduce any tendency for it to form a vacuum by keeping the speed down, while the second screw can have a comparatively high speed, since the water it acts upon is first set in motion by the forward screw.

From the foregoing it will be seen that my

invention is especially adapted to meet the peculiar conditions incident to the operation of tandem screws.

A somewhat similar condition to the above is found in operating dynamo-electric machines. The number of revolutions per minute of a dynamo of large size is limited by the strength of the devices holding the winding in place against the centrifugal force. A smaller revolving element can without danger make more revolutions per minute or until its peripheral speed is the same or substantially the same as that of the larger element. From the above it will be seen that I can with advantage utilize my invention in connection with dynamos having different diameters and obtain equal amounts of energy from both. In a similar way the equalization of the work offers advantages in connection with centrifugal blast-engines, &c.

The particular formation of the secondary wheel is only an illustrative means for attaining the desired end. I may construct the buckets of the primary and secondary wheels alike and cause the secondary wheel to rotate faster by suitably forming the driven machine.

Particular mention has been made of causing the wheels to perform equal amounts of work; but I do not wish to be understood as limiting myself to this, since by properly arranging the buckets and the fluid-discharging device or devices one wheel may do more work than the other. For example, instead of a one-to-one relation, the primary and secondary wheels may have a one-to-two relation.

In Figure 1 of the accompanying drawings, which illustrates one embodiment of my invention, is shown a turbine connected to propellers in a more or less diagrammatic manner. Fig. 2 is a detail view showing the propeller-blades detached from the wheels. Fig. 3 is a velocity-diagram for the buckets located beneath it, and Fig. 4 and 5 are similar views.

Referring to the drawings, 1 represents the primary wheel, and 2 the secondary wheel. The primary wheel is mounted on the hollow shaft 3 and the secondary wheel on the solid shaft 4. On the hollow shaft is mounted a propeller or screw 5, having blades of suitable size and shape. On the solid shaft is mounted a propeller or screw 6, having blades of suitable size and shape; but the diameter is less than that of the first-mentioned screw.

Mounted on the casing or other support is a nozzle 7 of suitable construction, which receives steam or other elastic fluid from a suitable source and discharges it against the buckets of the primary wheel at a predetermined velocity. The nozzle may be expanding or non-expanding in character and is preferably, although not necessarily, of the

sectionalized type to discharge the motive fluid in the form of a solid jet. It is desirable to provide two or more nozzles and to distribute them around the wheel at points equidistant to balance the strains thereon. The motive fluid leaves the primary wheel 70 with a certain velocity and strikes the buckets of the secondary wheel at a predetermined angle, and this without the intervention of intermediate buckets. The entering and discharge angles of the primary-wheel 75 buckets and the shape and size of the propeller-blades are such that the latter rotate at a definite predetermined speed. The entering and discharge angles of the buckets on the secondary wheel and the shape and size 80 of the propeller-blades are such that the latter revolve at twice the speed of the former and perform an equal amount of work.

Figs. 3, 4, and 5 show suitable shapes for buckets with velocity-diagrams for three different conditions of speed. Fig. 3 shows a velocity-diagram and buckets for a two-wheel combination wherein the speed relation is one to one. Fig. 4 shows a velocity diagram and buckets for a two-wheel combination 90 wherein the speed relation of the buckets is one to two. The difference in angles of the buckets is apparent from inspection. Fig. 5 shows a velocity-diagram and buckets for a two-wheel combination wherein 95 the speed relation of the buckets is one to three. The angular difference of the buckets in this arrangement over that of Fig. 1 is apparent.

In the following-table the respective values 100 are shown:

	$\frac{n_1}{n_2}$	1	2	3	
	t_g	0.818	0.29	0.278	105
	x°	17° 40'	16° 10'	15° 30'	
	t_g	0.25	0.25	0.25	
β_1	x°	14°	14°	14°	110
	t_g	0.563	0.59	0.51	
	x°	29° 22'	27° 30'	27°	115
	t_g	0.4	0.4	0.4	
β_2	x°	21° 50'	21° 50'	21° 50'	120

In accordance with the provisions of the patent statutes I have described the principle of operation of my invention, together with the apparatus which I now consider to represent the best embodiment thereof; but I desire to have it understood that the apparatus shown is only illustrative and that the invention can be carried out by other means.

What I claim as new, and desire to secure by Letters Patent of the United States, is—

1. In an elastic-fluid turbine, the combination of a nozzle or fluid-discharging device, a primary bucket-wheel receiving motive fluid from the nozzle or fluid-discharging device, and a secondary bucket-wheel receiving motive fluid directly from the primary wheel, the buckets of the secondary wheel being so shaped that its speed exceeds that of the primary wheel.
2. In an elastic-fluid turbine, the combination of a nozzle, a primary bucket-wheel receiving motive fluid from the nozzle, a secondary bucket-wheel receiving motive fluid directly from the primary wheel, the buckets of the wheels being so shaped that the speed of the secondary wheel exceeds that of the

primary wheel, and primary and secondary shafts connected respectively to the said wheels.

3. An elastic-fluid turbine comprising primary and secondary bucket-wheels, a nozzle and shafts connected to the wheels, in combination with load devices connected respectively to the shafts, the secondary wheel and load device connected thereto revolving at a speed greater than that of the primary wheel and its connected load device.

In witness whereof I have hereunto set my hand this 16th day of September, 1904.

JOHANN STUMPF.
